UNITED STATES PATENT OFFICE.

LLEWELLYN HENRY FLORY, OF ASHLEY, PENNSYLVANIA.

SHEARS.

1,037,827.

Specification of Letters Patent. Patented Sept. 3, 1912.

Application filed September 15, 1911. Serial No. 649,502.

To all whom it may concern:

Be it known that I, LLEWELLYN H. FLORY, a citizen of the United States, residing at Ashley, in the county of Luzerne and State 5 of Pennsylvania, have invented a new and useful Shears, of which the following is a specification.

It is the object of the present invention to provide a means whereby, when the blade 10 members of a pair of shears are brought together, in the act of cutting, the said blade members will be pressed together.

Specifically, the invention aims to provide an anti-friction element held between 15 the head of the connecting rivet, and one blade member, there being a race in the under surface of the head of the rivet, in which the anti-friction member moves, the base of the race being inclined with respect 20 to the adjacent, outer face of one blade member, so that when the blade members are brought together, in the act of cutting, the anti-friction member will ride from the deeper end of the race, toward the shal- 25 lower end thereof, thereby forcing the blade members together.

A further object of the invention is to provide means for anti-frictionally separating the blades of a tool of the class de- 30 scribed, when the blades of the tool are thrust together, through the instrumentality of the means hereinbefore mentioned.

With the foregoing and other objects in view which will appear as the description 35 proceeds, the invention resides in the combination and arrangement of parts and in the details of construction hereinafter described and claimed, it being understood that changes in the precise embodiment of in- 40 vention herein disclosed can be made within the scope of what is claimed without departing from the spirit of the invention.

In the accompanying drawings,—Figure 1 shows in plan, a pair of shears equipped 45 with the device constituting the subject-matter of the present invention. Fig. 2 is a section on the line 2—2 of Fig. 1, the cutting edges of the members of the shears being separated; Fig. 3 is a section on the 50 line 3—3 of Fig. 1, the blades of the shears being closed together; Fig. 4 is a perspective of the pivot element which connects the

blades of the shears; Fig. 5 is a view similar to Fig. 3, but showing a slight modification of the invention; and Fig. 6 is a side 55 elevation showing a still further modification of the invention, parts being broken away, in order to disclose the anti-friction members which separate the blades.

The shears shown in Fig. 1 comprise a primary blade 1 and a secondary blade 2, the primary blade 1 having a handle 3, and the secondary blade 2 having a handle 4. Intermediate their ends, the blades 1 and 2 are united for pivotal movement, as is 60 common, by a pivot element denoted generally in Fig. 2 by the reference character 5.

The pivot element 5 comprises a head 6, adapted to overhang the outer face 17 of the blade member 1, the head 6 being connected with a shank 7 which extends through the blade member 1. The blade member 1 is free to rotate upon the shank 7, and this blade member may also slide transversely, to a small extent, upon the 70 shank. The shank 7 merges into a polygonal shoulder 8, the shoulder 8 being engaged in an opening in the secondary blade 2, the blade 2 being thus held against rotation, upon the shoulder 8. The shoulder 8, pref- 80 erably does not extend entirely through the blade 2. The shoulder 8 terminates in a spindle 9, which is threaded, the spindle 9 protruding beyond the outer face of the secondary blade 2. Upon the threaded 85 spindle 9, a nut 10 is mounted, the nut 10 engaging the outer face of the secondary blade member 2.

The head 6 of the pivot element 5 is equipped in its under surface with a ball 90 race 11. This ball race 11 is located adjacent the handles 3 and 4 of the members 1 and 2. The ball race 11 curves around the shank 7 of the pivot element 5. The ball race 11 is deeper at one end 12 than 95 at the other end 15. The deeper end 12 of the ball race 11 is located adjacent the cutting edge 14 of the primary blade member 1. The base 16 of the ball race 11 is inclined with respect to the adjacent face 17 100 of the primary blade member 1.

In the ball race 11 are disposed balls 18, which may be of a common diameter.

In that form of the invention which ap-

pears in Fig. 5, the head of the pivot element is denoted by the numeral 19, the polygonal shank by the numeral 20, the threaded spindle by the numeral 21, and the nut by the numeral 22; the numeral 23 indicating the primary blade member and the numeral 24 indicating the secondary blade member. The ball race is indicated at 25, and the balls at 26, the balls, in the present instance, being of different diameters.

5 In that form of the invention which appears in Fig. 6, the shears is shown in the form of a pair of tinner's snips, whereas in Fig. 1, the shears are shown as of the sort employed by tailors.

10 In Fig. 6, the primary blade member is denoted by the numeral 27, and the secondary blade member by the numeral 28. These blade members 27 and 28 are connected by a 20 pivot element 29, the construction of which is identical with the construction of the pivot element 5, hereinbefore described. In the inner face of the secondary blade member 28 there is a ball race 30, in which are mounted balls 31, the balls 31 being adapted to engage the inner face of the primary blade member 27. It is to be understood that the balls 31 protrude beyond the inner face of the member 28 to an exceedingly 25 small extent only; in fact, only far enough to furnish an anti-frictional support for the primary blade 27.

15 The operation of the device, referring specifically to that form of the invention which appears in Fig. 1, is as follows, presupposing that the device is positioned as shown in Fig. 1, so that the shallower end 15 of the race 11 is disposed downwardly: When the blade members 1 and 2 are separated, to 30 space their cutting edges apart, the balls 18 will ride toward the deeper end 12 of the ball race 11. When, however, the blade members 1 and 2 are closed together, in the act of cutting, the balls 18 will ride toward 40 the shallower end 15 of the ball race 11. Obviously, by the foregoing operation, the inner faces of the levers 1 and 2 will be crowded together, and thus, the cutting edges of the blades will be maintained in 45 close and intimate contact, during the cutting operation.

50 Obviously, as appearing in Fig. 3, but one of the balls 18 will, theoretically, be effective to crowd the members 1 and 2 together. 55 In practice, however, the balls 18 may be varied slightly in diameter, due to defects in manufacture; and likewise, the foremost ball 18 may become flattened somewhat. Therefore, a plurality of the balls 18 are 60 shown.

65 That form of the invention appearing in Fig. 5, wherein the balls 26 are of varying diameters, possess the following advantages. If the balls 26 are of different diameters, so that several of them may be operative at the

same time, the blade members 1 and 2 will be thrust together, without tilting the blade member 1 transversely; whereas, in that form of the invention which appears in Fig. 3, the blade member 1 may be tilted transversely, to a slight extent, provided that the said blade member fits somewhat loosely upon the shank 7 of the pivot element 5.

70 When the device is employed in connection with a heavy pair of shears, such, for instance, as tinner's snips shown in Fig. 6, secondary anti-friction members 31 may be interposed between the blades 27 and 28, to off-set the thrust exerted by the balls 18 or 26, against the blade member 27. It is only 75 when excessively heavy material is to be cut, that the anti-friction members 31 are employed.

80 It will be observed that the ball race 11 lies within the contour of the head 6 of the pivot element 5, and since the diameter of the head 6 is less than the width of the blade member 1, it will be impossible for the balls 18 or 26 to drop out of the ball race 11 when 85 the cutting edges of the shears are separated.

90 Having thus described the invention, what is claimed is:—

1. A tool including a pivot element; and coöperating parts comprising a primary blade rotatable and transversely slidable 95 upon the pivot element, and a head upon the pivot element overhanging the outer face of the primary blade; one of which coöperating parts is provided with a race, the base 100 of which is inclined with respect to the adjacent face of the other coöperating part; a rotatable, anti-friction member movable in the race and adapted to engage the base of the race and the adjacent face of said other coöperating part; and a secondary blade 105 fulcrumed upon the pivot element, the primary blade being located between the head and the secondary blade.

2. A tool including a pivot element; and coöperating parts comprising a primary blade rotatable and transversely slidable 110 upon the pivot element, and a head upon the pivot element overhanging the outer face of the primary blade; one of which coöperating parts is provided with a race, the base of 115 which is inclined with respect to the adjacent face of the other coöperating part; a rotatable, anti-friction member movable in the race and adapted to engage the base of the race and the adjacent face of said other coöperating part; and a secondary blade fulcrumed upon the pivot element, the primary blade being located between the head and the secondary blade; and a secondary anti-friction device held for rotation between the blades.

3. A tool comprising crossed blades; a pivot element connecting the blades at their point of crossing, and provided with a head overhanging the outer face of one blade, 130

there being a race in the under surface of the head, the base of the race being inclined with respect to the adjacent, outer face of the said blade; and a rotatable, anti-friction 5 element in the race, and adapted to engage the base of the race and the adjacent face of said member.

In testimony that I claim the foregoing as my own, I have hereto affixed my signature in the presence of two witnesses.

LLEWELLYN HENRY FLORY.
